UNITED STATES PATENT OFFICE.

CLARENCE D. PLATT, OF BRIDGEPORT, CONNECTICUT.

ENTRANCE-SWITCH.

1,252,492.

Specification of Letters Patent.

Patented Jan. 8, 1918.

Application filed March 3, 1917. Serial No. 152,256.

To all whom it may concern:

Be it known that I, CLARENCE D. PLATT, a citizen of the United States of America, residing at Bridgeport, Connecticut, have 5 invented a new and useful Entrance-Switch, of which the following is a specification.

My invention relates particularly to an inclosed type of switch.

The main object is to provide a simple, 10 inexpensive but reliable construction which can be operated under normal circumstances either with the box open or closed, but which can be locked in the open circuit position. Another object is to provide such a construction 15 with means for automatic opening of the circuit when the box is opened. Another object is to provide for the automatic opening of the circuit when the box is closed. Another object is to provide for a quick 20 break of the circuit. Another object is to provide a construction, the parts of which can be very readily assembled.

In its preferred form the invention is 25 illustrated in the accompanying two sheets of drawings in which—

Figure 1, is a front view of the construction of my invention, the box being shown closed and locked with the parts in the open circuit position. This also shows a meter 30 attached.

Fig. 2, is a side view of the construction embodying my invention. The switch handle is shown in full lines in the open circuit position and in dotted lines in the closed 35 circuit position.

Fig. 3, is a side view showing the operating handle in the closed circuit position and the box open.

Fig. 4, is a front view on a larger scale 40 showing the switch in the open circuit position and the box open.

Fig. 5, is a vertical section on the plane of the line 5—5, of Fig. 4.

Fig. 6, is a perspective view of the movable switch member, part being broken away.

Fig. 7, is a detail sectional view showing the movable switch member and stationary contacts in the closed circuit position.

The insulating base 10 carries all the 50 ducting parts of the switch except the movable switch member. Stationary contacts 11 and 12 are suitably secured to the base and provided with binding screws 11' and 12' respectively. The other stationary contacts 13 and 14 are secured to the base by 55 the screws 15 and 16 which constitute the

center contacts for the usual fuse plugs. The screw sockets 17 and 18 for the fuse plugs are electrically connected to the members 19 and 20 which are provided with 60 binding screws 19' and 21'. The stationary contacts of the switch are preferably mounted in recesses such as 22 and 23.

The insulating base is preferably mounted in a box consisting of the body portion 25 and cover 26 hinged thereto. The base may be secured to the bottom of the box by means for instance of screws such as 27.

The movable switch member consists of 70 an insulating cross bar 28 carrying the laminated arch-shaped contacts 29 and 30. U-shaped springs 31 and 32 have their front ends inserted in the ends of the cross bar 28 and their rear arms pressing against the front face of the back of the box. Lugs 75 such as 33 may be employed to assist in preventing outward movement of these springs. The sides of the insulating base serve to prevent movement of the springs 80 toward each other. The operating handle 34 is provided with a shaft 35 which extends through the sides of the box and is provided with an off-set crank portion 36. The springs 31 and 32 press the cross bar outward so that it presses against the shaft and 85 its off-set portion 36. In the open circuit position the tension of the springs holds the shaft in such a position that the handle 34 presses against the stop 37.

The switch is closed by moving the handle 90 from full line position in Fig. 2 to the dotted line position, that is, by pulling the handle downward. This action rotates the shaft 35 and the off-set 36 presses against 95 the top of the cross bar 28 and forces the two movable switch members 29 and 30 down into contact respectively with the contact plates 11, 13 and 12, 14 as shown in Fig. 7. In coming to this position the handle strikes 100 against the shoulder 38 carried by the cover 26 which is hinged to the box 25. The tension of the springs 31, 32 holds the handle in this position when the cover is closed. A plate 40 may be provided on the upper 105 surface of the cross bar 28 to take up the wear due to the friction of the off-set 36 in operating the switch.

Preferably there is an insulating barrier 41 between the ends of the upper and lower switch contacts. There are also insulating 110 barriers 42 and 43 between the two oppositely movable switch members 29 and 30.

The lower insulating member 43 serves to prevent the movable switch member from falling downward when the parts are being assembled and the insulating shoulders 44 and 45 serve as stops to limit the upward movement of the cross bar 28. The handle and shaft are held in place by the cotter pin 46. By removing this cotter pin the handle and shaft may be readily withdrawn. 5 This releases the movable switch member which may be taken out without the use of any tools. The parts are of course assembled in reverse order. When the shaft is inserted and the handle is operated to close 10 the switch, the movement of the off-set 36 is sufficient to force the cross bar and the movable switch contacts into their proper places.

The switch may be locked when in the 20 open circuit position by means of a padlock 47 whose hasp passes around the handle and through the flange 48. The handle may also be secured in the open circuit position by means of a seal and wire 49 passing through 25 the opening 50 in the flange 48 and through the opening 51 in the cover.

When the circuit is closed and the switch handle in the dotted position of Fig. 2, the 30 opening of the cover 26 and the movement with it of the shoulder 38 forces the switch handle upwardly to such a point that the off-set 36 is affected by the springs 31 and 32 so as to throw the switch open with a snap action.

35 When the box is open of course the switch may be operated by hand but if by accident the switch is left closed when the cover is open, the closing of the cover from the position shown in Fig. 3, will bring the flange 40 52 to bear against the end of the handle 34 and move the handle upwardly sufficient so that the springs 31 and 32 can throw the switch open. If it is then intended to leave the switch in a closed circuit position, the 45 handle must be deliberately operated.

The construction shown is particularly adapted for the attachment of a meter such as 53 in Fig. 1, to the upper end of the box and the wiring is readily effected as shown, 50 the main line conductors coming in through the conduit 54 and being connected to the lower switch contacts. The upper switch contacts are conveniently connected to the meter through the bushing 55 and the wires 55 from the meter lead back into the box through the bushing 56 and then out through conduit 57. This prevents tampering with the wires at, or adjacent, the switch contacts or the meter.

60 I claim:

1. In a switch construction, an insulating base, stationary contacts carried thereby, an insulating cross bar, arch shaped switch contacts carried by said cross bar, said base having insulating projections on the face there-

of forming guides for said cross bar, springs for pressing said cross bar away from said base, an operating shaft having an offset engaging said cross bar and stops for limiting the movement of said operating shaft. 70

2. In a switch construction, stationary and movable switch members, a box inclosing the same comprising a body and a hinged cover, a shaft for operating the movable switch member having a handle disposed exteriorly of the box, and a flange on the cover in position when the cover is open to engage the handle in its closed circuit position and to shift said handle, as the cover is closed, into its open circuit position. 75 80

3. In a switch construction, an insulating base having upper and lower projecting insulating portions, stationary switch contacts mounted on opposite sides of said upper and lower insulating portions, an insulating cross bar movable between the upper and lower insulating portions, switch contacts carried by said movable member at opposite sides of said upper and lower insulating portions for coacting with the stationary 85 switch contacts, spring means for pressing said insulating member away from said base and hand operated means for pressing said member and the contacts carried thereby toward said base. 90 95

4. In a switch construction, the combination of a box having forwardly projecting guides, an insulating base located between said guides but spaced apart therefrom, stationary contacts carried by said base, movable contacts, an insulating cross bar carrying said movable contacts, U-shaped spring arms connected to said cross bar and held in position between said base and said guides, and means for operating said cross bar and 100 the switch contacts carried thereby. 105

5. In a switch construction, the combination of an insulating base, stationary contacts carried thereby, spaced insulating projections on the insulating base at opposite 110 sides of the cross bar for guiding said cross bar with relation to said base, movable switch contacts carried by said cross bar, an operating shaft having an offset portion for operating said cross bar in one direction and 115 springs for operating said cross bar in the opposite direction.

6. In a switch construction, stationary and movable switch members, a box for inclosing the same comprising a body and a 120 hinged cover, an operating shaft extending through said box and having a handle outside of said box, a shoulder carried by the cover in position to move the operating handle from the closed circuit position toward 125 the open circuit position when the cover is being opened with the switch closed, and a flange carried by the cover in a position to engage the handle when the cover is open for the purpose of moving the handle from 130

the closed circuit position toward the open circuit position.

7. In a switch of the character set forth, an insulating base having spaced projections on the face thereof forming a guide channel, a cross bar guided in said channel, contacts carried by said cross bar, relatively stationary contacts on the base adapted to be bridged by said contacts on the cross bar, U-shaped springs at the opposite ends of the cross bar and each having one end connected with the cross bar and its opposite end bearing against a relatively stationary support, and means for forcing the cross bar inward against the tension of said U-shaped springs.
8. In a switch of the character set forth, an insulating base having spaced projec-

tions on the face thereof forming a guide channel, a cross bar guided in said channel, contacts carried by said cross bar, relatively stationary contacts on the base adapted to be bridged by said contacts on the cross bar, U-shaped springs at the opposite ends of the cross bar and each having one end connected with the cross bar and its opposite end bearing against a relatively stationary support, means for forcing the cross bar inward against the tension of the U, a box inclosing the switch construction and comprising a box body and a hinged cover, and a stop on the cover for engaging and actuating the switch operating means in the closing movement of the cover.

CLARENCE D. PLATT.
